INVENTOR,

ALBERT M. TORRANCE.

BY *Franklin Scott*, ATTORNEY.

UNITED STATES PATENT OFFICE.

ALBERT M. TORRANCE, OF BENNINGTON, VERMONT.

SEAM-DAMPENER.

No. 865,827.

Specification of Letters Patent.

Patented Sept. 10, 1907.

Application filed April 15, 1903. Serial No. 152,663.

To all whom it may concern:

Be it known that I, ALBERT M. TORRANCE, of the village of Bennington, in the county of Bennington and State of Vermont, have invented certain Improvements in Seam-Dampeners Used in the Manufacture of Collars, of which the subjoined description, in connection with the accompanying drawings, constitute a specification.

In manufacturing folding collars as an article of wearing apparel, in joining the top to the band by stitching in the well known manner, a seam is produced of several thicknesses, many more in fact than exist in either the top or the band. In finishing the collar the usual practice has been to starch the collar and then iron it out flat, after which a narrow strip just above and close to the upper edge of the seam is moistened with water which softens the starch sufficiently to permit the top to be bent down over the upper edge of the seam in which folded condition it is finished and dried. Various means have been devised to do this seam dampening so that it will be truly done, or uniformly distant from the edge of the seam, and without getting the seam too wet or leaving it too dry. And it has been found difficult to devise automatic machines for doing this effectually, accurately and rapidly. One of the greatest difficulties hitherto has been to guide the collar through the machine so that the dampened streak would exactly follow the line of the proposed fold when the top was turned over and finished. Where the hand and eye are more or less relied on to do this accurately, the operation of the machine is necessarily much retarded.

To overcome these obstacles to accurate and rapid work is the object in part of this invention. This has been accomplished by the construction and adaptation of a spring presser foot to a guide shoe and mounting both these coöperative members upon an adjustable member so that the guide may be set to work on either side of the wetting bands, thereby furnishing facilities for running the collars through the machine with either end in the lead.

In some existing machines a movable guide shoe has been used without a presser foot which could be pinched onto the front edge of the table of the machine and adjusted by rule of thumb to its working position and a finger of the operator used to hold the seam of the collar to its place in the shoe while the collar passed under the wetting band, but this shoe has been only manually and not mechanically adjustable.

My invention is fully illustrated in the drawings wherein

Figure 1 shows a front elevation of my invention with some parts shown in vertical section to disclose hidden parts. Fig. 2 is a right hand end elevation of the same, and Fig. 3 is a plan view thereof with the top arm removed to let into view the upper shaft and guide

shoe. Fig. 4 shows perspectives of coöperative faces of the shoe and presser foot. Fig. 5 is a cross-section of a collar seam in position between shoe and presser foot. Fig. 6 is a detail view showing a modification of a presser foot having a flat bearing face.

My apparatus is mounted in a suitable frame preferably a standard 1 having a base 2, table 3 and an overhanging arm 4 to support the upper water trough and for other purposes. In this frame is journaled the main driving shaft 5 which carries a driving pulley 6 at one end and a band sheave 7 at the free end. It also carries a gear 8 between its bearings which meshes with gear 9 on the upper shaft 10. This shaft is carried in a trunnion box 11 pivoted in the main standard 70 and sliding box 12 which is free to move vertically a short distance in its bearing in standard 13. Over box 12 is a spring 14 and follower 15 which are controlled by a thumb screw 16 whereby the belt carried by sheave 17 which is carried on the free end of shaft 75 10 can be set up against the belt or band carried on sheave 7.

On the end of the arm 4 is carried a water trough 18 which is adapted to be adjusted vertically by the screw 19 beneath it. This trough can slide vertically 80 between the uprights 20, 20, of arm 4. On it the sheaves 21, and 22, 22, are mounted so that the middle sheave 21 can dip into water carried in the trough. A wetting band 23 passes over all these sheaves and under the sheave 17 and in operation this band is kept 85 saturated to the desired extent by the sheave 21 which takes up in its groove sufficient water from the water in the trough into which it dips, to moisten the band as it runs over it. If this should be insufficient the band may be shifted from the upper to the under side 90 of the sheave 21 so that it will itself dip into the water in the trough. The tension of this band can be adjusted by raising or lowering the trough by means of the set screw 19. Any slack in band 23 occasioned by the irregular springing upwards of sheave 17 will 95 be taken up by spring 40 under trough 18. A similar trough 24 is located beneath the table on the base of the machine which moves horizontally in slideways 26, 26, and can be adjusted by the set screw 27. This trough is so arranged that a horizontal movement of 100 it will change the tension on the band. A wetting band 28 is provided which runs over the sheave 7 on the main shaft, under the sheaves 29, 29, of trough 24 and over the central sheave 30. This band is kept moistened from the water taken up by sheave 30 or if 105 this is insufficient the band can be adjusted to run under the sheave through the water in the same way as is provided for the upper band. Both troughs are supplied with water in any convenient way from any suitable source. A portion of the table around the 110 sheaves 7 and 17 is cut away to permit the two bands to meet at or near the level of the table.

Beneath the table is a horizontal slide 31, which can be moved in clips 32, 32, by means of an adjusting screw 33 at the right of the table which takes into a screw-threaded aperture in the end of the slide. Attached to this slide is the guide shoe 34 the upper side of which stands a little above the point of contact of the two bands. At the left hand end of the slide is attached an arm 35, which is bent upwardly, passing through a slot in the table, and its free end extends out over the guide shoe and has attached to it the presser foot 36. This foot is adapted to operate directly over the shoe by pressing against the upper side of the shoe anything passing between them. The arm 35 is made sufficiently slender and of such material as will act as a spring which exerts its force to urge the presser foot against the shoe. The under side of the foot is creased so as to present parallel V-shaped ridges to the material passing under it. The guide shoe also has similar raised ridges r , r , which coöperate with the ridges on the presser foot. The ridges r , r , of the shoe are flared in front as shown in Fig. 3 to facilitate the ready entrance of the end of the seam between the foot and shoe, and if it happens that the end of a seam is not accurately entered these flaring ribs will gradually guide or force the seam around into a correct position. An uncreased presser foot shown in Fig. 6 will work well on many kinds of collars, hence I do not restrict myself to the creased foot.

It is apparent that by reason of the presser and shoe being both attached to a common slide member, by means of the screw 33, both foot and shoe may be set to operate on either side of the bands, according to whichever end of a collar the operator cares to enter first. As multi-ply collars are usually put together, a very thick seam is formed where the top and neck-band are joined, and in the process of finishing the bulk of the thickness of this seam appears on the inside of the collar. The edges of this seam are very prominent and present well defined edges, so that these edges or boundaries of the seam afford the means for guiding the collar through between the shoe and the presser foot. The space or concavity in the shoe between the ridges r , r , is gaged to receive the protuberant edges of the seam, and the shoe is long enough to cause this seam to drop in between the ridges which thus point the leading end of the collar in its true direction between the wetting bands, while the similar ridges on the bottom of the presser foot assist in the same way and act to prevent the collar from sluing around in its passage. This characteristic is well shown in Fig. 5 in which the collar is shown in cross-section in solid black lines.

The machine is adjusted and operated as follows:—Wetting bands of appropriate sizes are selected and adjusted in working position on the sheaves. Ordinarily, a finer band is used to wet the face of the seam than the back, and this would go on the upper set of sheaves. The water supply is then regulated and the proper amount is graduated for both troughs. The pressure between the two bands at their point of contact between sheaves 7 and 17 is adjusted by means of the pressure screw 16. This is so adjusted that the upper shaft will yield to the passage of an extra thickness in a seam—as for instance, at each end of the seam

where the infolded ends of the finished edge of the top are stitched into the seam. Then the tension of the bands and any slack in either is disposed of by the tension screws 19 and 27. Then the guide-shoe is set either to the right or left of the bands by means of the adjusting screw 33, when the machine is ready for operation. The collars are then fed to the bands through between the shoe and presser foot by the attendant as fast as they can be handled, an operator being easily able to pass fifty collars through per minute as it is only necessary to just enter the end of the seam so that it can be seized between the bands which will then draw it through without further attention, the formation of the opposing faces of the presser foot and shoe acting together to conduct the collar in the proper direction.

I therefore claim as my invention and desire to secure by Letters Patent, the following:

1. In a seam dampener of the character described, the combination with the wetting devices, of a seam guide consisting of a shoe having upstanding guiding ridges, a presser foot which coöperates therewith having upstanding ridges, and means connected with one of said guiding members for imparting to it a yielding pressure, substantially as specified. 90
2. In a seam dampener of the character described, the combination with a shoe and a presser foot, both attached to an adjustable member, of means connected with the latter for adjusting it laterally with reference to the wetting devices at the dampening point, substantially as specified. 95
3. A collar seam guide for use in seam dampeners consisting of two coöperative members, the opposing operative faces of which have parallel ridges against which the seam contacts in passing between them, means for maintaining pressure therebetween, and means for propelling the collar between them, substantially as specified. 100
4. The combination in a seam dampener of a water trough, a plurality of band sheaves mounted to rotate above said trough, a wetting band carried by said sheaves, 105 the relative arrangement of said sheaves being such that the lower edge of one of said sheaves can dip into the water and thereby carry water to the band which runs over its top, and an actuating sheave, over which the band runs located at the dampening point, substantially 110 as specified. 115
5. The combination in a seam dampener of two wetting bands mounted to run over two sets of sheaves in connection with a water supply for moistening each band, said bands being adapted to contact with each other between two adjacent sheaves each of which belongs to its corresponding set, with a collar guide consisting of a guide shoe having longitudinal ridges between which the seam moves and a presser foot adapted to bear on the seam above the shoe, means for actuating the bands and means 120 for applying yielding pressure to the presser foot, substantially as specified. 125
6. A collar guide for seam dampening machines consisting of a concave member having guiding ridges between which the seam can run, and a presser foot opposed to a 130 said concave member, both members being attached to a common adjustable slide, substantially as described. 135
7. The combination with the upper shaft and sheave, upper wetting band and upper trough and sheaves carried thereon, of a stationary support for said trough and means 130 interposed between the support and trough for taking up slack in the wetting band occasioned by the lifting of the upper shaft and sheave due to irregularities passing between the wetting bands, substantially as specified. 140
8. A guide for seam dampeners, consisting of an upper and an under member, one of which is provided with means for directing the fabric passing between them to the dampening devices, a movable device to which both members are attached, and means for adjusting said device laterally with reference to the dampening devices, substantially as specified. 145

9. A guide for seam dampeners, consisting of an upper and an under member, one of which is provided with means for directing the fabric passing between them to the dampening devices, in combination with means for adjusting said guide laterally with reference to the dampening devices, substantially as specified.

10. In a moistening machine, the combination of the moistening devices, means for mounting and operating the same, two guides juxtaposed to the moistening devices, for the purpose specified, and a yielding presser foot lying over the guides and coöperating therewith.

11. In a moistening machine, the combination of the moistening devices, means for mounting and operating the

same, a tang, a spring-actuated presser foot carried thereby, and two guide members mounted on the tang and co-acting with the presser foot.

12. In a collar dampening machine and in combination, means for supplying moisture to a collar, and in advance thereof a grooved collar guide, and a presser coöperative with said guide.

In witness whereof I have hereunto subscribed my name at Bennington, Vermont, this 4th day of April, A. D., 1903.

ALBERT M. TORRANCE.
